METHOD OF INSERTING MATERIALS IN ENVELOPES

Application filed December 12, 1929. Serial No. 413,480.

This invention relates to a method of inserting within sealed envelopes, such as positive column tubes, materials which are difficult to handle due to their explosive nature or due to the ease with which they combine with moisture or the atmosphere or which may be difficult or dangerous to handle for other reasons, or it may be merely desirable to handle the material in the manner to be described herein. Some examples of materials which are difficult to handle are the metals comprising the alkali or alkali earth groups of metals such as sodium, potassium and caesium.

15 An object of the invention is to provide a method whereby any material and in particular a material which is dangerous or difficult to handle may be inserted safely and easily within an envelope which envelope 20 may or may not be sealed.

The invention will be more apparent from the following description taken in connection with the drawing in which:

Figure 1 shows a positive column tube with 25 a capsule placed within the electrode.

Figure 2 shows a partial section of the capsule.

In my co-pending application, Serial No. 413,481 filed on even date herewith, there 30 has been described a method whereby materials and particularly such materials as the alkali and alkali earth metals of which sodium, potassium, and caesium are examples, are sealed in a casing forming a capsule which is readily handled. The materials to be utilized need not necessarily be difficult to handle since the method described herein may also be used with any kind of material and it may be desirable only to apply 35 them in the manner of this invention. The capsule consisting of a casing and the material sealed therein, is inserted within the envelope in which the material is subsequently to be liberated from its enclosing casing 40 and subjected to heat which causes the casing of the capsule to crack and open freeing the material enclosed therein which material may flow or spatter about within the envelope or become vaporized and become distributed 45 in the envelope in its vapor form.

The capsule 1 shown in Figure 2 consists of a casing 2 of glass in which the material 3 to be liberated and preserved is sealed. Preferably the glass casing has thick walled ends 4 for a purpose to be subsequently discussed. Scratches 5 are made in the thick walled portions of the capsule as well as elsewhere. The entire capsule need not be entirely filled with material and the space 6 may be evacuated if desirable in the manufacture of the capsule.

In order to break the casing to liberate the material therein, it is subjected to heat in any way. The heat breaks the casing which has been weakened by the scratches. Where 55 the enclosing casing is of glass having portions of its walls of uneven thickness and the capsule is heated, uneven strains are set up in the casing which augmented by the weakening scratches assists in breaking the casing 60 to liberate the enclosed material.

Other forms and types of capsules, it is apparent will also serve the purpose. Also a compound may be inserted within the casing which upon heating yields a gas and the material or metal desired. The gas liberated 75 will assist in breaking the casing.

The heating of the capsule to open the enclosing casing is accomplished by heating the envelope adjacent to the capsule by a flame. 80 A better way, however, is to place the capsule in contact or close proximity with a high resistance metal, such as nickel, also within the envelope and this metal is then heated in any manner, the heat from the metal being transferred to the capsule and breaking it, to release the material sealed therein. One manner in which this metal may be heated is by placing a coil about the envelope so that it also surrounds the high resistance metal 85 within the envelope and a high frequency electrical current passed through the coil which inductively heats the metal. The heat from the metal is transmitted to the capsule which cracks and opens liberating the material sealed therein. The capsule may also be heated by placing it in contact with a metallic wire heated by an electric current passing through the wire.

The process described broadly above is par- 100

- ticularly applicable to the insertion of an alkali or alkali earth metal within the envelope of a positive column tube and adjacent to the electrodes. A capsule within 5 which a metal such as potassium is sealed, is inserted within the envelope 8 and preferably within each of the electrodes 9 provided at either end of the tube. The tube is then evacuated through a connecting tube 10 connected to an evacuating pump. The occluded gases are then driven off from the electrodes and the tube walls. The driving off of the occluded gases is accomplished by subjecting the tube and the electrodes to heat in a manner known to the art and will not be described 15 here other than to say that such heating may be carried out by passing through the tube a discharge current of sufficient density to bring about the requisite degree of heating. 20 This temperature to which the electrodes and tube is subjected by this heating is regulated so as to be not sufficiently high to crack and break the capsule and liberate the metal within the capsule. The evacuating of the 25 tube and driving off of the occluded gases may require several heatings.

In order to cause breaking of the capsule casing, the casing is subjected to an even higher temperature than is necessary to drive 30 off occluded gases. The high temperature may be obtained by passing between the electrodes of the tube a discharge current having a density sufficiently high to cause breaking of the capsule. The heavy current is 35 passed through the tube for a short time only and the pump continues evacuation of the tube to remove the additional occluded gases thrown off by the tube and electrodes as a result of the increased temperature to which 40 they have been subjected. The discharge current is supplied from the generator 12 through the transformer 14 and variable reactance 16.

If the electrodes of the positive column 45 tube are of high resistance material, such as nickel, these electrodes can more advantageously be heated to a temperature sufficient to break the capsule by surrounding the electrode within the envelope by an external coil 50 carrying a high frequency current. This method of heating the electrodes is also applicable to electrodes of metals not having a high resistance, such as copper, but it requires a higher current and a longer time to raise 55 the temperature of the electrode sufficiently high to break the capsule so that for this reason the first method described is better suited.

Upon the capsule casing breaking, the 60 metal sealed therein spatters or flows about the electrode. If the electrode is a cylindrical shell the greater part of the metal will be deposited upon the inner wall of the electrode. Where a more general distribution of 65 the potassium or metal is desired, the electrode may be perforated or made of metal

screen. Upon breaking of the capsule casing the potassium spatters over the entire electrode practically as well as upon the inner wall of the electrode chamber of the envelope.

70 Preferably it is desirable to have the capsule casing anchored within the electrode or envelope of the tube. Where the capsule is within the electrode and the electrode made of sheet material, the sheet may be snugly wrapped about the capsule when forming the electrode. When the capsule casing cracks and liberates the enclosed metal, the casing remains anchored and does not leave loose bits within the envelope. It is clear that the capsule need not be placed within the electrode but may be outside of the electrode so long as it is adjacent thereto. If other means are provided for heating the capsule it is obvious that the capsule need not be placed adjacent to the electrode inasmuch as the electrode serves as a means of heating the capsule when the capsule is placed in or adjacent thereto.

80 Having described my invention it is understood that various modifications may be made therein without deviating from the scope and it is specifically understood that the invention is not limited by the examples described herein except as limited in the accompanying 85 claims.

90 What is claimed is:

1. A method of introducing materials within an evacuated envelope comprising sealing the material within a glass capsule, 100 scratching the surface of the glass capsule, to provide a weakened portion, inserting the capsule within the envelope, evacuating the envelope, and breaking the capsule at the weakened portion to release the material.

105 2. A method of introducing materials within an evacuated envelope comprising sealing the material within a glass capsule, scratching the surface of the glass capsule, to provide a weakened portion, inserting the capsule within the envelope, evacuating the envelope, and subjecting the capsule to heat which breaks it at the weakened portion and releases the material from the capsule into the envelope.

110 3. A method of inserting a material within a sealed and evacuated positive column lighting tube envelope having electrodes comprising sealing the material within a glass capsule, scratching the glass wall of the capsule, inserting a capsule within the envelope in close proximity to each electrode, evacuating the envelope, subjecting the electrode to a high temperature which breaks the capsule while continuing the evacuation, charging the envelope with an inert gas, and sealing the envelope.

115 4. A method of inserting a metal difficult to handle within an evacuated and sealed positive column lighting tube envelope having

electrodes comprising sealing the metal within a glass capsule, scratching the capsule, inserting the capsule within the electrode, evacuating the envelope, driving off occluded gases by passing an electrical current between the electrodes, passing a higher electrical current between the electrodes than utilized to drive off occluded gases which heats the electrode and heats and breaks the capsule

10 while evacuation continues, charging the envelope with at least one illuminant material, and sealing the envelope.

5. A method of inserting a metal difficult to handle within an evacuated and sealed positive column lighting tube envelope having electrodes with perforated walls comprising sealing the metal within a glass capsule, scratching the capsule, inserting the capsule within the electrode and anchoring it therein, evacuating the envelope, driving off occluded gases by passing an electrical current between the electrodes, passing a higher electrical current between the electrodes than utilized to drive off occluded gases which

20 heats the electrode and heats and breaks the capsule while evacuation continues, charging the envelope with at least one illuminant material, and sealing the envelope.

6. A method of inserting a metal difficult to handle within an evacuated and sealed positive column lighting tube having high resistance electrodes comprising sealing the metal within a glass capsule, scratching the capsule, inserting the capsule within the electrode, evacuating the envelope, driving off occluded gases by passing an electrical current between the electrodes, heating the electrode to a higher temperature than utilized to drive off occluded gases by placing each electrode

30 at the center of a high frequency field to break the capsule while continuing evacuation of the envelope, charging the envelope with at least one illuminant material, and sealing the envelope.

45 7. The method of making a luminous gas discharge tube having a cathode treated with volatile thermo emissive material which comprises enclosing the said material in a frangible capsule weakened at one or more points by a scratch or scratches in the surface thereof so that the vapor pressure of the contents increased by the application of heat readily ruptures the weakened capsule and spatters the contents in the vicinity, positioning the capsule within the tube and in the vicinity of the cathode, evacuating and scavenging the tube and applying sufficient heat to the capsule to create sufficient pressure of the contents to burst the capsule weakened by the said scratches.

8. A method of making a luminous gas discharge tube having a cathode treated with a volatile thermo emissive material which comprises enclosing the said material in a frangible capsule having walls of substan-

tially different thickness a portion of which walls are so thin that they readily yield to internal pressure and burst on the application of sufficient heat, introducing the capsule into the luminous tube in proximity to the cathode, evacuating and scavenging the tube, heating the capsule sufficiently to burst it at the said weakened portion and spattering the contents thereof upon the surface of the cathode.

In testimony whereof I affix my signature.
